(57) **CLAIM**

The ornamental design for a telephone handset, as described and shown.

DESCRIPTION

FIG. 1 is a perspective view of the telephone handset, showing the new ornamental design;

FIG. 2 is a top elevation thereof;

FIG. 3 is a bottom elevation thereof;

FIG. 4 is a front elevation thereof;

FIG. 5 is a rear elevation thereof;

FIG. 6 is a right side elevation thereof;

FIG. 7 is a left side elevation thereof;

FIG. 8 is a perspective view of a second embodiment of the telephone handset, in which the belt clip shown in FIGS. 1-7 has been removed;

FIG. 9 is a top elevation thereof;

FIG. 10 is a bottom elevation thereof;

FIG. 11 is a front elevation thereof;

FIG. 12 is a rear elevation thereof;

FIG. 13 is a right side elevation thereof; and,

FIG. 14 is a left side elevation thereof.
